Primary Examiner — Michael A. Pratt

(74) *Attorney, Agent, or Firm* — Burr & Brown, PLLC

(57) **CLAIM**

The ornamental design for a key button, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a perspective view;

Fig. 1.2 is a front view;

Fig. 1.3 is a bottom view;

Fig. 1.4 is right-side view;

Fig. 1.5 is top view;

Fig. 1.6 is a rear view; and

Fig. 1.7 is a left-side view.

Fig. 2.1 is a perspective view;

Fig. 2.2 is a front view;

Fig. 2.3 is a bottom view;

Fig. 2.4 is right-side view;

Fig. 2.5 is top view;

Fig. 2.6 is a rear view; and

Fig. 2.7 is a left-side view.
